UNITED STATES PATENT OFFICE

2,515,174

PENCIL SHARPENER

Victor R. Abrams, Rockford, Ill., assignor of one-half to George E. O'Leary, Rockford, Ill.

Application November 28, 1947, Serial No. 788,514

22 Claims. (Cl. 120—96)

1

This invention relates to pencil sharpeners, and has for its principal object the provision of a portable device adapted to be placed on top of a desk, or wherever it is to be used, as distinguished from the conventional stationary type that is fastened permanently to the wall.

Another important object of my invention is to provide a pencil sharpener of the type in which a rotary frame carries two helical cutters that have gears on one end thereof working in a stationary internal gear, so that the cutters turn on their axes as they are revolved, the rotary frame, in accordance with the present invention, being supported on a base for operation on a vertical axis, and having drive means connected to the vertically disposed drive shaft thereof, arranged to be operated by downward pressure on a spring returned oscillatable operating lever, as distinguished from the rotation of a crank on the conventional type.

In the preferred form, the drive means consists of a flexible wire cable, which is wrapped around and is arranged to transmit drive frictionally to the drive shaft in only one direction upon downward thrust of the operating lever, the wire cable slipping relative to the shaft when returned by the same spring that returns the operating lever. Otherwise the drive means, in order to permit the kind of push-down operation described, necessitates the use of a pawl and ratchet mechanism between the drive means and the rotary frame.

Another important object of my invention is to provide a device of the kind mentioned, in which the operating lever is so connected or related to the drive means that there is maximum leverage at the commencement of the down stroke to set the rotary frame in motion, and thereafter leverage is so related to the resistance to turning and the increasing resistance of the return spring that the device operates with substantially uniform pressure on the operating lever throughout the operating stroke. This result is obtained in one way with the wire cable form of drive means, and in two other ways where racks and pinions combined with pawl and ratchet means are used.

The invention is illustrated in the accompanying drawings, in which—

Fig. 1 is a perspective view of a portable desk model pencil sharpener made in accordance with my invention;

Fig. 2 is a central vertical section through the sharpener on a larger scale;

2

Fig. 3 is a plan view of the sharpener with the cover removed;

Fig. 4 is a view similar to Fig. 2 showing a modified or alternative construction;

Fig. 5 is a similar view of still another construction;

Fig. 6 is an isolated plan view of the drive means for the device of Fig. 5;

Fig. 7 is a horizontal section on the line 7—7 of Fig. 4 to better illustrate the drive means used in that form;

Fig. 8 is a horizontal sectional detail on the line 8—8 of Fig. 4, showing the return spring for the operating lever, and

15 Figs. 9 and 10 are two views of the pawl and ratchet connection between the drive means and the rotary frame in Fig. 4.

Similar reference numerals are applied to corresponding parts throughout the views.

- 20 Referring first to Figs. 1 to 3, the reference numeral 11 designates the supporting base for the pencil sharpener, on which a cover 12 of suitable form and suitable material is mounted to enclose the pencil sharpener mechanism and at 25 the same time provide a chip receptacle. An opening may be provided in the base, or in the cover, with a closure that is slidable or rotatable to and from a closed position to enable dumping chips from time to time, or the cover itself may be removed for that purpose, whichever is preferred. An L-shaped bracket 13 is suitably secured to the base 11, and has a block 14 suitably secured to the upwardly projecting arm 15 thereof, on which is supported the stationary base 16 for the cutter mechanism. This mechanism consists of a rotary frame 17 carrying a pair of spaced cylindrical helical cutters 18 disposed in the usual diametrically opposed converging relation on opposite sides of the tubular holder end 19 of the frame 17, as in the well known conventional stationary pencil sharpeners, the cutters 18 having drive pinions 20 on their lower ends meshing with an internal gear ring 21 fixed in the base 16, so that when the frame 17 is turned 30 by means of its downwardly projecting spindle end 22, that is coaxially arranged with respect to the holder 19 and extends through the bearing portion 23 of the base 16, the cutters 18 will turn on their axes as they revolve with the frame and 35 will accordingly sharpen the lower end of the pencil 24 inserted vertically in the holder 19, as shown in Fig. 2, the pencil being held in the hand of the operator against turning during the sharpening operation, when no other means is 40 provided for that purpose. The spindle 22, in 45

other words, corresponds to the spindle on the conventional stationary sharpener, to which the usual hand crank is attached, and the base 16 corresponds to the stationary frame of such a device. However, in accordance with my invention, the spindle 22 has a wire cable 25 wrapped around it preferably two or three times to serve as a frictional drive means, one end of the cable being fastened to a take-up arm 26, which is spring pressed in one direction by a torsion spring 27, and the other end portion of which extends over a pulley 28 mounted on the operating bell crank 29 and is fastened at its extremity, as at 30, to the arm 15 of the bracket 13. The take-up arm 26 is pivoted in the bearing 31 on the bracket 13, and the spring 27 has its coiled portion surrounding the bearing 31, and has the upper end extending therefrom for connection, at 32, with the take-up arm 26, and has the lower end extending therefrom for connection, as at 33, with the bracket 13. The operating bell crank 29 is pivoted at 34 in a bearing 35 on the upper end of the arm 15, and has the pulley 28 rotatably mounted, as at 35, on the lower end of the downwardly projecting arm 36 thereof. The other arm 37 of the bell crank lever 29 extends through a vertical slot 38 provided in the cover 12, and has a suitable operating knob 39 fixed on the projecting end thereof, as illustrated in Fig. 1. A curved sheet metal baffle plate 40 is provided on the base 16 on that side toward the slot 38, to prevent chips from being thrown from the cutters 18 through the slot 38 in the operation of the pencil sharpener, the cutters 18 being operable within the arc defined by the baffle plate 40. In that way all of the chips produced in the operation of the pencil sharpener are collected inside the device and there is no messing up of the desk top. The top opening 41 through which the pencil holder 19 extends freely is so located that it requires no protection and is too small, anyway, to permit escape of chips through it.

In operation, a pencil is inserted vertically into the holder 19, point end down, and is held by the operator with one hand while he depresses the knob 39 with the other hand. The depression of the knob 39, of course, causes lever 29 to be oscillated from the full line position shown in Fig. 2 toward the dotted line position, thereby turning the spindle 22 through the medium of the wire cable 25 that is wrapped around it and, accordingly, turning the rotary frame 17 to revolve the cutters 18 around the point end of the pencil. The cutters 18 having their pinions 20 operating in the internal ring gear 21 turn on their axes as they revolve with the frame to do the cutting, as in other pencil sharpeners. The drive occurs only in one direction, namely, on the down stroke of the knob 39. The take-up arm 26 merely returns the cable to its initial position and the lever 29 with it, because there is so little resistance to the sliding of the cable 25 relative to the spindle 22 afforded by the lever 29 in the return movement in relation to the resistance afforded by the pencil sharpener mechanism and the friction of the cutters against the pencil, the cable accordingly slides freely around the spindle in the return movements. It is important to note in Fig. 2 that the point of attachment of the cable to the bracket 13, at 30, is so located with respect to the lever 29 that in the first ten or fifteen degrees of movement of the lever from the full line position toward the dotted line position, the pulley 28 does not turn, and, hence, the lever

29 exerts its maximum mechanical advantage as it pulls forward a length of cable equivalent to the lineal measurement of the movement of the pulley 28 with the lever 29. This maximum mechanical advantage is important, because there is maximum resistance to turning the pencil sharpener mechanism at the start of each sharpening operation. After the initial ten or fifteen degrees of movement of the lever 29, when the attached end portion of the cable 25 passes the plane indicated by the dot and dash line a—b (Fig. 2), the pulley 28 will turn as the lever 29 is moved further, because from that point on twice as much cable length is payed out for a given lineal movement of the pulley 28 with the lever 29, and, while that necessarily involves an increase in the speed at which the resistance of the spring is built up, it does not result in any noticeable increase in resistance to depression of the knob 39, because through this particular angularity of movement of the lever 29, the device is operating through the most favorable angularity in so far as the position of the take-up arm 26 is concerned. In explanation of this last statement, attention is called to Fig. 3 in which the take-up arm 26 is shown in its fully retracted position where the spring 27 exerts minimum resistance to movement of the arm 26. In the initial movement of the lever 29, the pull on the arm 26 is in the direction indicated by the cable 25 in Fig. 3, and obviously, the lever 29 operates in this initial movement on the shortest moment arm, which, however, increases the farther the knob 39 is depressed. Hence, by the time the arm 26 has moved through about 45° in a counter-clockwise direction, the pull of the cable 25 is at a most advantageous angle, and this advantageous range corresponds to the end range of movement of the lever 29 to the extreme position indicated in dotted lines in Fig. 2. Consequently, the operator is not aware of any perceptible difference in resistance to movement of the knob 39 at any point in the stroke; and the operation is accordingly very smooth. Two or three downward strokes on the knob 39 are usually enough to resharpen a pencil. The operation takes no longer with this device than with the old crank type. The cable 25 is not apt to be fouled by the chips and pencil lead deposited in the sharpener, whereas gear mechanisms of whatever design are subject to that possibility. This drive mechanism, is moreover, much more economical to manufacture, and will last indefinitely without lubrication.

In Fig. 5, I have shown a modified or alternative construction, in which the bracket 13a has an operating lever 29a, pivoted thereon at 34a, and arranged to operate a gear sector 42 that is pivoted at 43 to the stationary base 16a of the sharpener mechanism, and meshes with a pinion 44 suitably mounted on the pin 46a, and arranged to transmit drive to the rotary frame 17a of the cutter mechanism through a suitable pawl and ratchet drive connection, like that shown in Figs. 9 and 10. A roller 45, mounted on a pin 46, projecting from the side of the lever 29a, is arranged to engage an arm 47 projecting from the gear sector 42, whereby to operate with maximum mechanical advantage at the start of the sharpening operation and with less and less leverage thereafter, as can be seen from a comparison of the full line position of the parts with the dotted line position shown in Fig. 5. A return spring 27a has its coiled portion surrounding the pivot pin 43, and has one end 33a fixed to

the base 16a, and the other end 32a attached to the gear sector 42, so as to return the gear sector to the starting position and the lever 29a with it when the knob on the outer end of the lever 29a is released at the lower end of the stroke. In this sharpener, as in the sharpener of Figs. 1 to 3, a curved baffle plate 40a is preferably provided on the base 16a on that side toward the slot 38a in the cover 12a, to prevent escape of chips through the slot in the operation of the sharpener. The pencil to be sharpened is inserted in the holder 19a, similarly as in the sharpener previously described, and the sharpener mechanism is supported on the bracket 13a by the block 14a. It is believed that the operation of this sharpener needs no explanation, in view of the similarity to the construction first described.

The sharpener shown in Figs. 4 and 7 to 10 involves the use of an elongated pinion 48, arranged to be turned by means of a rack 49 that meshes with it and is pivotally connected, at 50, with one arm 36b of the bell crank operating lever 29b, which, in turn, is pivotally mounted, as at 34b, on the upwardly projecting arm 15b of the bracket 13b, the other arm 37b of the lever 29b being equipped with a knob, like the knob 39 (Fig. 1), for depression of the operating lever. The other end of the rack 49 is pivotally connected, as at 51, with a link 52 disposed in parallel relation to the arm 36b, and pivotally mounted at its other end, as at 53, on the stationary base 16b of the sharpener mechanism. This base 16b is supported on the bracket 13b, as shown at 14b. A spring 27b surrounds the bearing for the pivot 34b, and has one end 33b anchored on the bracket 13b and the other end 32b connected to the arm 36b of the lever 29b to return the lever to the starting position at the end of each operating stroke. Here again, it should be manifest that the operating lever 29b operates with maximum mechanical advantage at the start of the stroke, due to the position of the rack 49 in such closely spaced relation to the pivot 34b at the start. Then, as the lever 29b is depressed farther and farther, the rack 49 is slid farther and farther down on the pinion 48, meanwhile, of course, turning the pinion by reason of the accompanying endwise movement of the rack. The pinion 48 is carried on a pin 54, 50 suitably fixed at its lower end in the bracket 13b and supported at its upper end in a bearing hole provided in the lower end of the drive spindle 22b, which transmits drive to the rotary frame 17b of the cutter mechanism, similarly as in the construction of Fig. 5. The spindle 22b is attached to a cupped disk 55, which has its recessed face down, to provide a shielded mounting for the pawl 56, to prevent fouling of the pawl by chips and lead in the operation of the sharpener. The pawl 56 is spring pressed toward engagement with the pinion 48 by means of a spring 57, which is coiled around the pivot pin 58 of the pawl, and has one end connected to the pawl and the other end anchored to the disk 55. In the downward strokes of the lever 29b, the pinion 48 is turned in a counterclockwise direction as viewed from above, as indicated by the arrow 59 in Fig. 9. Drive is, therefore, transmitted through the pawl 56 and disk 55 to the spindle 22b, which, in turn, transmits drive to the rotary frame 17b, similarly as the spindle 22 of Fig. 2 drives the frame 17. In the return strokes of the lever 29b, the pinion 48 is, of course, turned in the opposite direction and over-

5 runs the pawl 56, so that drive is transmitted to the sharpener mechanism only in the down strokes of the lever 29b. The operation of this sharpener, it is believed, does not require any further discussion, in view of the general similarity in this construction to the others.

It is believed the foregoing description conveys a good understanding of all of the objects and advantages of my invention. The appended claims have been drawn with a view to covering all legitimate modifications and adaptations.

I claim:

1. A pencil sharpener comprising, in combination, a supporting frame structure providing thereon a pivot, a drive spindle mounted for rotation in a bearing on said frame in right angle relation to said pivot, cutter means carried on one end of said spindle to turn therewith, a manually oscillatable operating lever turning on said pivot, and means operatively connecting said lever and spindle and so arranged as to be operative only on the strokes of said lever in one direction for turning said spindle, whereby the cutter means is adapted to be turned intermittently in one direction.

2. A pencil sharpener comprising, in combination, a supporting frame structure providing thereon a substantially horizontal pivot, a drive spindle mounted for rotation in a substantially vertical bearing on said frame, cutter means carried on the upper end of said spindle to turn therewith, a manually oscillatable operating lever turning on said pivot, and means operatively connecting said lever and spindle and so arranged as to be operative only on the down strokes of said lever for turning said spindle, whereby the cutter means is adapted to be turned intermittently in one direction.

3. A pencil sharpener comprising, in combination, a supporting frame structure providing thereon a pivot, a drive spindle mounted for rotation in a bearing on said frame in right angle relation to said pivot, cutter means carried on one end of said spindle to turn therewith, a manually oscillatable operating lever turning on said pivot, and means operatively connecting said lever and spindle and so arranged as to be operative only on the strokes of said lever in one direction for turning said spindle, whereby the cutter means is adapted to be turned intermittently in one direction, said means operating with different mechanical advantage in different portions of the operating stroke of the lever, the greatest mechanical advantage being afforded in the first portion of each stroke.

4. A pencil sharpener comprising, in combination, a supporting frame structure providing thereon a substantially horizontal pivot, a drive spindle mounted for rotation in a substantially vertical bearing on said frame, cutter means carried on the upper end of said spindle to turn therewith, a manually oscillatable operating lever turning on said pivot, and means operatively connecting said lever and spindle and so arranged as to be operative only on the down strokes of said lever for turning said spindle, whereby the cutter means is adapted to be turned intermittently in one direction, said means operating with different mechanical advantage in different portions of the operating stroke of the lever, the greatest mechanical advantage being afforded in the first portion of each stroke.

5. A pencil sharpener comprising, in combination, a supporting frame structure providing thereon a pivot, a drive spindle mounted for rota-

tion in a bearing on said frame in right angle relation to said pivot, cutter means carried on one end of said spindle to turn therewith, a manually oscillatable operating lever turning on said pivot means operatively connecting said lever and spindle and so arranged as to be operative only on the strokes of said lever in one direction for turning said spindle, whereby the cutter means is adapted to be turned intermittently in one direction, and spring means tending to return said lever to a starting position at one end of its stroke.

6. A pencil sharpener comprising, in combination, a supporting frame structure providing thereon a substantially horizontal pivot, a drive spindle mounted for rotation in a substantially vertical bearing on said frame, cutter means carried on the upper end of said spindle to turn therewith, a manually oscillatable operating lever turning on said pivot, means operatively connecting said lever and spindle and so arranged as to be operative only on the down strokes of said lever for turning said spindle, whereby the cutter means is adapted to be turned intermittently in one direction, and spring means tending to return said lever to a starting position at the upper end of its stroke.

7. A pencil sharpener comprising a portable supporting base, a cutter frame rotatably mounted on said base on a substantially vertical axis and having means on the upper end for supporting a pencil to be sharpened and having a downwardly extending drive spindle, rotating and revolving cutters carried on said frame for operation on the end of the pencil, means for rotating said cutters while they are revolved with said frame, a manually oscillatable operating lever pivoted with respect to said base on a substantially horizontal axis, and means operatively connected with said drive spindle and with said lever to turn said spindle for cutting action only on the down strokes of said lever.

8. A pencil sharpener comprising a portable supporting base, a cutter frame rotatably mounted on said base on a substantially vertical axis and having means on the upper end for supporting a pencil to be sharpened and having a downwardly extending drive spindle, rotating and revolving cutters carried on said frame for operation on the end of the pencil, means for rotating said cutters while they are revolved with said frame, a manually oscillatable operating lever pivoted with respect to said base on a substantially horizontal axis, and means operatively connected with said drive spindle and with said lever to turn said spindle for cutting action only on the down strokes of said lever, said means operating with different mechanical advantage in different portions of the operating stroke of the lever, the greatest mechanical advantage being afforded in the first portion of each down stroke.

9. A pencil sharpener comprising a portable supporting base, a cutter frame rotatably mounted on said base on a substantially vertical axis and having means on the upper end for supporting a pencil to be sharpened and having a downwardly extending drive spindle, rotating and revolving cutters carried on said frame for operation on the end of the pencil, means for rotating said cutters while they are revolved with said frame, a manually oscillatable operating lever pivoted with respect to said base on a substantially horizontal axis, means operatively connected with said drive spindle and with said

lever to turn said spindle for cutting action only on the down strokes of said lever, and spring means tending to return said lever to a starting position at the upper end of its stroke.

10. A pencil sharpener comprising a portable supporting base, a cutter frame rotatably mounted on said base on a substantially vertical axis and having means on the upper end for supporting a pencil to be sharpened and having a downwardly extending drive spindle, cutter means carried on said frame for operation on the end of the pencil, a manually oscillatable operating lever pivoted with respect to said base on a substantially horizontal axis, a flexible belt element wound around said spindle, having one end portion operatively connected with said lever so as to be pulled upon each down stroke of the lever to turn the spindle in one direction for cutting action, and spring actuated take-up means connected to the other end of said belt to return the belt and lever to a starting position.

11. A pencil sharpener comprising a portable supporting base, a cutter frame rotatably mounted on said base on a substantially vertical axis and having means on the upper end for supporting a pencil to be sharpened and having a downwardly extending drive spindle, cutter means carried on said frame for operation on the end of the pencil, a manually oscillatable operating lever pivoted with respect to said base on a substantially horizontal axis, a flexible belt element wound around said drive spindle and having one end fixed with respect to said base, said lever having a portion bearing against the fixed end portion of said belt between the fixed end and the spindle and arranged to exert a pull on the belt upon each down stroke of the lever to turn the spindle in one direction for cutting action, and spring actuated take-up means connected to the other end of said belt to return the belt and lever to a starting position.

12. A pencil sharpener comprising a portable supporting base, a cutter frame rotatably mounted on said base on a substantially vertical axis and having means on the upper end for supporting a pencil to be sharpened and having a downwardly extending drive spindle, cutter means carried on said frame for operation on the end of the pencil, a manually oscillatable operating lever pivoted with respect to said base on a substantially horizontal axis, a flexible belt element wound around said drive spindle and having one end fixed with respect to said base, a pulley rotatably mounted on said lever and engaging the fixed end portion of said belt between the fixed end and said drive spindle, and arranged to move toward the fixed end and past it in the down strokes of said lever to exert a varying pull on the belt in each down stroke of the lever to turn the spindle in one direction for cutting action, and spring actuated take-up means connected to the other end of said belt to return the belt and lever to a starting position.

13. A pencil sharpener comprising a portable supporting base adapted to serve as a chip receptacle, a cutter frame rotatably mounted on said base on a substantially vertical axis and having means on the upper end for supporting a pencil to be sharpened and having a downwardly extending drive spindle, cutter means carried on said frame for operation on the end of the pencil, a manually oscillatable operating lever pivoted with respect to said base on a substantially horizontal axis, means operatively connected with said drive spindle and with said lever

to turn said spindle for cutting action, a housing on said base for the mechanism described having a substantially vertical slot provided in the wall thereof through which the manually engageable end of said lever extends for operation, and chip baffle means stationarily supported in said housing on that side of the cutter frame toward the slot.

14. A pencil sharpener comprising a portable supporting base, a cutter frame rotatably mounted on said base on a substantially vertical axis and having means on the upper end for supporting a pencil to be sharpened and having a downwardly extending drive spindle, cutter means carried on said frame for operation on the end of the pencil, a manually oscillatable operating lever pivoted with respect to said base on a substantially horizontal axis, one-way drive means connecting the drive spindle with the cutter frame, a gear for turning the spindle, a gear sector pivotally mounted with respect to said base on a substantially horizontal axis in spaced substantially parallel relation to the axis of said lever and meshing with said gear, and means operatively connecting said lever and sector to transmit rotary movement to the drive spindle so as to turn the cutter frame only on the down strokes of said lever.

15. A pencil sharpener comprising a portable supporting base, a cutter frame rotatably mounted on said base on a substantially vertical axis and having means on the upper end for supporting a pencil to be sharpened and having a downwardly extending drive spindle, cutter means carried on said frame for operation on the end of the pencil, a manually oscillatable operating lever pivoted with respect to said base on a substantially horizontal axis, one-way drive means connecting the drive spindle with the cutter frame, a gear for turning the spindle, a gear sector pivotally mounted with respect to said base on a substantially horizontal axis in spaced substantially parallel relation to the axis of said lever and meshing with said gear, an arm extending from said sector and operatively engaged by a projection on said lever, so as to transmit oscillatory movement to the sector with decreasing leverage in the down strokes of said lever and turn said spindle so as to transmit drive to the cutter frame only on the down strokes of said lever, and spring means tending to return said segment and lever to a starting position.

16. A pencil sharpener comprising a portable supporting base, a cutter frame rotatably mounted on said base on a substantially vertical axis and having means on the upper end for supporting a pencil to be sharpened and having a downwardly extending drive spindle, cutter means carried on said frame for operation on the end of the pencil, a manually oscillatable operating lever pivoted with respect to said base on a substantially horizontal axis, a drive gear for transmitting drive to said spindle, one-way drive means operatively connecting the drive gear and spindle so as to turn the cutter frame only in one direction on the down strokes of said lever, a rack meshing with said drive gear, and means operatively connecting said rack with said lever.

17. A pencil sharpener comprising a portable supporting base, a cutter frame rotatably mounted on said base on a substantially vertical axis and having means on the upper end for supporting a pencil to be sharpened and having a downwardly extending drive spindle, cutter

means carried on said frame for operation on the end of the pencil, a manually oscillatable operating lever pivoted with respect to said base on a substantially horizontal axis, a drive gear for transmitting drive to said spindle, one-way drive means operatively connecting the drive gear and spindle so as to turn the cutter frame only in one direction on the down strokes of said lever, a rack meshing with said drive gear, and means including an extension of said lever for supporting said rack for endwise and vertical movement parallel to itself while operatively connecting said rack with said lever, said gear being elongated sufficiently to remain meshed with said rack throughout its range of vertical movement.

18. A pencil sharpener comprising a portable supporting base, a cutter frame rotatably mounted on said base on a substantially vertical axis and having means on the upper end for supporting a pencil to be sharpened and having a downwardly extending drive spindle, cutter means carried on said frame for operation on the end of the pencil, a manually oscillatable operating lever pivoted with respect to said base on a substantially horizontal axis, a drive gear for transmitting drive to said spindle, one-way drive means operatively connecting the drive gear and spindle so as to turn the cutter frame only in one direction on the down strokes of said lever, a rack meshing with said drive gear, means including an extension of said lever for supporting said rack for endwise and vertical movement parallel to itself while operatively connecting said rack with said lever, said gear being elongated sufficiently to remain meshed with said rack throughout its range of vertical movement, and spring means tending normally to move said lever to a starting position.

19. A pencil sharpener comprising, in combination, a base adapted to serve as a chip receptacle, a supporting frame structure carried thereon and providing thereon a substantially horizontal pivot, a drive spindle mounted for rotation in a substantially vertical bearing on said frame, cutter means carried on the upper end of said spindle to turn therewith, a housing on said base to enclose the mechanism described having a substantially vertical slot provided in the wall thereof, a manually operated lever oscillatingly turnable on said pivot and projecting outwardly through and movable vertically in said slot, the range of vertical improvement of the lever being substantially within the height of said housing, means operatively connecting said lever and spindle to turn the spindle in the oscillatory movement of the lever, and means to return the lever to elevated starting position.

20. A pencil sharpener comprising, in combination, a portable base, a frame rotatable on said base on a substantially vertical axis, rotating and revolving cutters carried on the upper end of said frame for operation on the end of a pencil to be sharpened, means for rotating said cutters while they are revolved with said frame, said frame having a downwardly extending drive spindle, a horizontal pivot on said frame, a housing on said base to enclose the aforesaid mechanism and having a vertical slot provided therein, a manually operated lever oscillatingly turnable on said pivot and extending outwardly through the slot in said housing and movable vertically therein, means operatively connecting said lever with said spindle for revolving said spindle in response to the lever on the manually operated down stroke, and spring means to re-

11

turn the lever to starting position without revolving the cutters.

21. A pencil sharpener comprising, in combination, a supporting frame structure providing thereon a pivot, a drive spindle mounted for rotation in a bearing on said frame in right angle relation to said pivot, cutter means carried on one end of said spindle to turn therewith, a manually oscillatable operating lever turning on said pivot, and means operatively connecting said lever and spindle and so arranged as to be operative on the strokes of said lever for revolving said cutters.

22. A pencil sharpener comprising, in combination, a supporting frame structure providing thereon a pivot, a drive spindle mounted for rotation in a bearing on said frame in right angle relation to said pivot, cutter means carried on one end of said spindle to turn therewith, a manually oscillatable operating lever turning on said pivot, and means operatively connecting said lever and spindle and so arranged as to be opera-

12

tive on the strokes of said lever for revolving said cutters, said means operating with different mechanical advantage in different portions of the operating stroke of the lever, the greatest mechanical advantage being afforded in the first portion of each stroke.

Certificate of Correction

Patent No. 2,515,174

July 18, 1950

VICTOR R. ABRAMS

It is hereby certified that error appears in the printed specification of the above numbered patent requiring correction as follows:

Column 9, line 52, for the word "segment" read *sector*;
and that the said Letters Patent should be read as corrected above, so that the same may conform to the record of the case in the Patent Office.

Signed and sealed this 7th day of November, A. D. 1950.

[SEAL]

THOMAS F. MURPHY,
Assistant Commissioner of Patents.
